UNITED STATES PATENT OFFICE.

EDWARD H. BELDEN, OF PITTSBURGH, PENNSYLVANIA, ASSIGNOR TO BELDEN ENGINEERING COMPANY, OF PITTSBURGH, PENNSYLVANIA, A CORPORATION OF PENNSYLVANIA.

INTERNAL-COMBUSTION ENGINE.

1,130,674.

Specification of Letters Patent. Patented Dec. 15, 1914.

Application filed December 26, 1911. Serial No. 867,764.

To all whom it may concern:

Be it known that I, EDWARD HALE BELDEN, a citizen of the United States, and a resident of Pittsburgh, county of Allegheny, 5 and State of Pennsylvania, have invented certain new and useful Improvements in Internal-Combustion Engines, of which the following is a specification.

My invention relates to internal combustion engines and has particular reference to improvements in the valves and valve gearing of internal combustion engines of the four-cycle type.

The objects of my invention are to simplify the construction and to lessen the cost of such engines; to eliminate the vibration and the noise incident to their operation; and to increase the power, efficiency and durability thereof.

My further purpose is to do away with the short-lived and noisy reciprocating valves and valve gearing now in common use and to substitute therefor a minimum number of large substantial parts that can 25 not easily be broken, that will offer the least possible resistance to the operation of the engine, and which will wear indefinitely without being reground or refitted.

A special object of my invention is to provide an engine of the class named with a nonvibratory, constantly lubricated admission and exhaust valve and to maintain it at a low temperature protected from the hot gases of the cylinder.

Still other objects of the invention are to provide an internal combustion engine having a cylinder which contains both the cylinder head and the necessary port-controlling means and from which both the head and the piston may be removed without disturbing the cylinder or said port-controlling means or gearing, and from which the valve may be removed without disturbing the cylinder or the valve gearing; and to provide an engine having valves and valve seats which shall be freely accessible upon removal of the cylinder head.

Another object of my invention is to provide a four-cycle engine that may be made and assembled, disassembled and reassembled by ordinary mechanics and in less time than other four-cycle engines.

A further object is to provide valves and valve gearing of such form and arrangement that the several cylinders of a multi-

ple engine may be economically formed in one block or casting.

Still further objects of my invention will appear hereinafter.

My invention resides in an internal combustion engine, which, in its simplest form, has a single-piece ported cylinder, a single-piece cylinder head, a single-piece valve which is incased by the cylinder and the head, a single valve operating member and a single actuating and timing device which connects the valve operating member with the crank shaft.

The valve requires little power for its operation. The simple structure here outlined is somewhat amplified in the higher developments of my invention but even in its multiple cylinder forms I prefer to use only one valve operating member and one driving device.

The invention will be readily understood upon reference to the accompanying drawings, which form part of this specification and in which I have depicted a preferred embodiment of my invention in a six cylinder internal combustion engine.

In the drawings: Figure 1 is a side elevation of my novel engine, four of the cylinders and part of the base being shown in vertical longitudinal section; Fig. 2 is a horizontal section substantially on the line 2^x-2^x of Fig. 1, several of the cylinder heads being removed; Fig. 3 is an enlarged vertical section on the line 3^x-3^x of Fig. 2; and Fig. 4 is a similarly enlarged vertical section on the line 4^x-4^x of Fig. 1.

I have here illustrated my invention as embodied in a water cooled multiple cylinder engine of a vertical type particularly adapted for use in automobiles. Its cylinders A, six in number, are arranged side by side in a single casting B. Various means may be employed for cooling the cylinder and valve seats. For example the casting B may contain a water space or jacket C which is common to all the cylinders. The water space extends from the top B' of the casting to a point near the lower ends of the cylinders. The bottom B'' of the cylinder casting is secured upon the top of the base D. The base contains the crank shaft E shown in dotted lines in Fig. 1. On one end of the shaft E is a fly wheel F. The other end of the crank shaft carries a sprocket wheel G the use of which

will be explained hereinafter. Each cylinder A contains a piston H, joined to the crank shaft E by a connecting rod L. The cylinders open through both the top and the bottom of the casting B. They have separate heads J. The head J of each cylinder is preferably wholly contained within the upper or outer end of the cylinder. I make these ends of the cylinder large enough to receive the pistons so that the latter may be inserted and removed through the tops of the cylinders after the cylinder casting B has been fastened to the base D. The heads are larger than the pistons and each head rests upon an annular shoulder a^2 , which distinguishes the piston containing portion a^3 of the cylinder from its head containing portion a^4 . Both cylinder portions a^3 and a^4 are cylindrical. They are preferably concentric. The portion a^4 is large enough to contain not only the head but also the valve K, about to be described. Each head has an annular flange J' that fits the upper part of the cylindrical bore a^4 . The lower end J^2 of each head J snugly fits the piston bore a^3 of the cylinder and the annular shoulder J^3 of the head rests upon the cylinder shoulder a^2 as before explained. The upper end of the bore a^4 of each cylinder is threaded to receive a locking ring L, which is screwed firmly upon the flanged top of the head, completing an oil and pressure tight joint between the head and the cylinder at that point. A key or set screw L' may be added to lock the head against rotation. The shoulder A^2 of the cylinder and the shoulder J^3 of the head are ground together and when the head is thus secured the shoulders form an oil and pressure tight joint between the lower end of the head and the cylinder. It will be observed that the concentricity of the cylinder and the head is insured by the close fitting of the upper end and the lower end of the head within the larger and the smaller bores a^4 and a^3 of the cylinder. The intermediate portion of each head J, between the flange J' and the shoulder J^3 , is cylindrical and concentric with the containing bore a^4 . While this portion, as herein shown, is larger than the piston bore a^3 , it is somewhat smaller than the bore a^4 and an annular cavity K' having parallel cylindrical walls is therefore formed between the cylinder and the head. The top of the cavity K' is formed by the underside of the head flange J'. The bottom of the annular cavity is formed by the cylinder shoulder a^2 on which the head rests. All of the walls of the cavity are finely ground and serve as seats for the valve K before referred to. The valves K are simple one-piece sleeves or rings that exactly fit their respective cavities K'. They are interchangeable. The inner and outer surfaces of each valve K are finely ground

and cylindrical and parallel. The top and bottom edges are also finely ground or finished and are parallel and perpendicular to the cylindrical surfaces.

In practice, the cross sectional dimensions of the valve K are approximately two thousandths of an inch smaller than the corresponding dimensions of the cavity K', leaving space for thin films of oil between all the opposed surfaces of the valve, cylinder and head. Each valve K contains at least one opening or port K², the same being of sufficient size to quickly admit and to quickly free the gases and is positioned about midway of the height of the valve. As shown in the drawings, I prefer to provide each valve with two diametrically opposite ports K², so that one revolution of the valve shall serve for eight successive strokes, two complete power operations, of the piston, as hereinafter explained. Each cylinder is provided with an admission port and passage A⁴ and an exhaust port and passage E^x, these being formed in the casting B. The ports A⁴ and E^x open into respective valve cavities K' in position to register with the ports K² in the valve K. The width of the space between the inlet and exhaust ports approximately equals the width of the port K² in the valve K. These dimensions may be considerably varied without departing from the invention but I prefer to maintain the described proportions and relation for the particular reason that after the valve has opened to permit the heated gases to exhaust, those portions of the valve which are heated by the exhaust gases are almost immediately cooled by the inrush of combustible mixture at the port A⁴. The time between the exhaust and the admission of mixture is proportionate to the distance that the valve has to travel between the ports E^x and A⁴.

In a multiple cylinder engine I prefer to pair the cylinders and connect the exhaust passages E^x of each pair as shown in Figs. 2 and 4. From the points of juncture the exhaust passages extend downward and open through the lower part of the casting B as shown in Fig. 4, wherein E^x represents the vertical extension of the united exhaust ports of two cylinders. E^{x2} represents the exhaust manifold of the engine. As indicated in Fig. 2, I prefer that the admission passages A⁴ of the several cylinders shall be independent and shall open through the outer face of the casting above the exhaust connections. The passages A⁴ are connected by an admission manifold A⁴² having two connections A⁴³ and A⁴⁴ with a suitable carbureter A⁴⁵. As best shown in Fig. 3, each head J contains a central cavity J⁴ hemispherical at the top and opening through the bottom of the head. This cavity, which obviously communicates with the piston containing portion a^3 of the

cylinder, constitutes the compression and combustion chamber of the engine. A central hole is provided in the top of the head and in this hole is the device for igniting the gases, preferably an electric spark plug M. Two passages J—A⁴ and J—E² are formed in the head. These open through the valve seat surface of the head, directly and respectively opposite the ports A⁴ and E² in the valve seat surface of the cylinder, hence these passages or ports of the head are in position to register with the ports K² in the valve K.

The valve operating mechanism is most clearly shown in Figs. 1, 2 and 3. Each member K is a combined valve and gear wheel; that is, the lower outer edge of each valve K is provided with gear teeth K³ constituting an integral gear wheel whereby the valve may be rotated in its valve chamber or cavity. The valve operating member is arranged on the side of the engine opposite the side which contains the several admission and exhaust ports. This valve operating member comprises a single shaft N having as many integral gear wheel portions N' as there are valves. Each cylinder is provided with an opening A N, at a point opposite the gear teeth on the valve and considerably below the level of the port K in the valve. This opening admits the operating gear N' into mesh with the gear teeth upon the valve. Obviously all of the openings A N are arranged in a horizontal line. The shaft N is held in suitable bearings N² provided on the side of the cylinder casting B as shown in Figs. 2 and 4. Such gears operate readily in either direction and are noiseless. At its end, the shaft N is provided with a sprocket wheel N³ and this is connected with the sprocket wheel G on the crank shaft by a suitable sprocket chain G⁴. The sprockets G and N³, and the sprocket belt G⁴ constitute the driver for the valve operating member or shaft N. The rotation of the crank shaft is thereby communicated to the several valves, and the latter are rotated constantly during the operation of the crank shaft. The sprockets G and N³ and the gears N' and K³ are so proportioned that the valves are caused to turn one-half of a revolution during each two revolutions of the crank shaft. It will be clear that the rotative speed of the valves is relatively low and that nothing short of the breakage of one of these heavy substantial parts can interfere with the proper action of the valve. The valve operating shaft and gears are contained by a horizontal duct O formed in the side of the cylinder casting. B⁴, B⁴ are the edges of the duct O, integral with the cylinder casting B. The opening between them is closed by a vertical plate B⁵ tightly bolted thereto and making the duct oil tight. The duct O and the several valve cavities K' are

in communication through the openings A N. The sprockets G and N³ and sprocket belt G⁴ are inclosed by a casing P, the upper end of which communicates with the duct O and the lower end of which communicates with the interior of the engine base D. An oil pump (not shown) forces oil into the duct O. The oil is distributed therefrom to the several valves by the gear wheels N' and K³. In the case of each valve, its rotation causes the oil to spread upon the outer surface of the valve whence it will work above and below the valve and spread upon the inner surface thereof. As before explained the differences of diameter, between the valve, the cylinder and the head, are so slight that only minute films of oil may occupy the spaces. These are in fact capillary spaces and while the oil will freely work into and occupy the spaces due to the rotation of the valve within the inclosing walls, the oil cannot easily be discharged from the spaces by either internal or external pressure. The films of oil constitute fluid packings for the joints. This fact makes it possible to adequately lubricate the valves and inclosing walls without danger of gas leakage from or to the cylinders at moments of compression, combustion and vacuum therein. It is clear also that it is practically impossible for any surface of the valve to engage any opposed surface upon the head or cylinder except through the medium of this minute film of oil which envelops the valve. In consequence the valve and valve seats will operate indefinitely without perceptible wear.

As shown in Fig. 3, the upper edge of each valve K is preferably provided with an annular oil groove K⁵ for an accumulation of oil, to better distribute the oil upon the inner surface of the valve. Very little of the oil thus supplied to the valve is wiped off at the ports, the greater part returning to the trough through the openings A N. It will thus be seen that the valves themselves, by reason of being provided with the gear teeth K³, constitute oil circulating pumps which not only pump the oil from the duct O into the valve cavities but carry the oil completely around the whole circumference of the cavities and return the surplus oil back into the duct O. This pump action of the valves insures the positive and thorough lubrication of these parts. The tight joint before alluded to, between the lower end of the head J and the cylinder prevents leakage of valve oil into the cylinder, a feature which is of distinct advantage.

As before explained the water space C within the cylinder casting extends to the top of the cylinders and cooling water is therefore supplied to all of the upper parts of the cylinders except those portions or areas which are occupied by the admission

and exhaust passages A^d , A^x , and the gear openings A , N . The cooling of the outer walls of the valve cavities and the outer portions of the valves is thus insured. Each head J contains a water space J^w . The water is supplied and discharged through pipes J^p , two of which are provided for each head. The top of the head contains a depression to admit, and afford easy access to, the firing plug M . The space J^w occupies nearly the whole of the head, only thin walls remaining. As before described, the head is deeper than the valve K , extending both above and below the same. The water space is likewise deep, its bottom being preferably below the level of the valve K and the water rising therein to a level above the top edge of the valve. In other words, the cooling surface of the valve wall of the head is practically co-extensive with the valve and the maintenance of the valve at a low temperature is positively insured. It is not material whether these walls which inclose or envelop the valve are cooled by water or by air, or by some other medium; the important point is that the valves and the inclosing walls are so formed and related that they are quite separate from the hotter portions of the cylinder and head and are fully exposed to the cooling medium.

The operation of the engine is according to the well known four-cycle principle and will be clearly understood from the foregoing detailed description of the operation of its several related parts. As explained valves K of the several engines derive motion from the crank shaft. The directions of rotation of the valves are indicated by arrows in Fig. 2. The rotation of each valve is, obviously, timed to suit the movements of the piston in its respective cylinder, and the moments of opening and closing the ports is determined by the relative positioning of the ports in the cylinder and by the relative width of the ports in the valve and the cylinder. The drawings clearly disclose these several relative positions and proportional dimensions. Starting with a valve port K^2 in register with the exhaust port, the action may be traced as follows: The cylinder is cleared or scavenged while the exhaust port E^x is open. As the valve rotates the port K^2 is moved away from the exhaust port and soon registers with the admission port A^d . At such time the piston is moving down and the explosive mixture will be drawn into the cylinder. Further rotation of the valve removes the port K^2 from the port A^d and closes the latter at about the time the piston begins to move up again. This upward stroke compresses the charge which is exploded at about the time the piston reaches the upper end of its stroke. Then follows the downward power stroke of the

piston. During these last two up and down strokes of the piston, the ports A^d and E^x are closed by the blank portion of the rotating valve but at about the end of the power stroke of the piston the valve will have rotated to the point of presenting its other port K^2 to the exhaust port E^x of the cylinder, thus completing the last of the four cycles and beginning the next series of operations or cycles.

Many modifications of my invention will readily suggest themselves to one who is skilled in the art, and I do not confine or limit the invention to the specific details of construction herein shown and described.

The valve construction herein shown comprises the subject matter of my co-pending application Ser. No. 659,204, and is not herein claimed.

Having thus described my invention I claim as new and desire to secure by Letters Patent:

1. In an internal combustion engine, a plurality of parallel cylinders, an individual cylindrical valve in and coaxial with each cylinder for controlling the inlet and exhaust of the gases, each cylinder having an opening in its wall, a single valve actuator entering said openings for simultaneously driving said valves and each of said valves being removable through its cylinder without disturbing the valve actuator.

2. In an internal combustion engine, a plurality of parallel cylinders, a rotating valve within each cylinder, each cylinder having an opening in its wall giving access to the valve therein, a single valve actuator entering all of said openings engaging all of said valves for the simultaneous rotation thereof, and each said valve being capable of being disengaged from the actuator merely by withdrawal from its operative position.

3. In an internal combustion engine, a plurality of parallel cylinders, a rotatable sleeve valve arranged in each cylinder for controlling the inlet and exhaust of the gases, each cylinder being provided with an opening through its wall giving access to the valve therein, a unitary actuator entering all of said openings and adapted to rotate all of said valves simultaneously, and each said valve being capable of removal from its cylinder while the actuator is in position.

4. In an internal combustion engine, a plurality of cylinders, rotatable sleeve valves coaxial with respective cylinders for controlling the inlet and exhaust of the gases, each valve having an integral gear on its periphery, each of said cylinders having an opening in its side wall giving access to said gear, and a shaft having a plurality of integral gears, one for each valve, adapted

- to enter respective openings and simultaneously rotate all of said valves, the valves and worm gears being capable of disengagement by simply withdrawing the 5 valves from their cylinders.
5. In an internal combustion engine a single block or casting containing a plurality of cylinder bores and means suitably closing the upper ends of said bores, in combination with a piston in each said bore, a crank shaft wherewith said pistons are connected, a rotatable valve provided in the upper part of each cylinder bore, each said cylinder having admission and exhaust 10 ports that are controlled by its valve and also having an actuator opening, a closed actuator duct formed in said block or casting, in communication with said actuator openings, a single actuator provided in said 15 duct and operating all of said valves, means whereby said actuator rotates said valves, said means permitting the withdrawal of valves without first removing the actu-

ator, and means whereby said actuator is driven by said crank shaft. 25

6. In an internal combustion engine a plurality of cylinders, a rotating valve in each cylinder, each cylinder having an opening in its wall giving access to the valve therein, an annular gear coaxial with and operatively related to each valve, valve actuating gears, one for each valve, projecting through the openings in the cylinder walls and engaging the valve gears, a rotating member carrying all of said valve actuating 30 gears, and each said valve being removable from its cylinder while the valve actuating gears are in operative position.

In testimony whereof, I have hereunto set my hand, this 20 day of Dec., 1911, in the 35 presence of two subscribing witnesses.

EDWARD H. BELDEN.
